CLAIM

I claim the ornamental design for a canopy for a vehicle, truck, light delivery vehicle or similar vehicle, as shown and described.

DESCRIPTION

FIG. 1 is a perspective rear view of an embodiment of a canopy for a vehicle, truck, light delivery vehicle or similar vehicle, showing my new design;

FIG. 2 is an exploded view thereof, shown from the rear;

FIG. 3 a perspective front view thereof;

FIG. 4 is another exploded view thereof, shown from the front;

FIG. 5 is a top view thereof;

FIG. 6 is a bottom view thereof;

FIG. 7 is a side view thereof;

FIG. 8 is a front view thereof;

FIG. 9 is a rear view thereof;

FIG. 10 is a perspective rear view of a second embodiment of a canopy for a vehicle, truck, light delivery vehicle or similar vehicle, showing my new design;

FIG. 11 is an exploded view thereof, shown from the rear;

FIG. 12 a perspective front view thereof;

FIG. 13 is another exploded view thereof, shown from the front;

FIG. 14 is a top view thereof;

FIG. 15 is a bottom view thereof;

FIG. 16 is a side view thereof;

FIG. 17 is a front view thereof; and,

FIG. 18 is a rear view thereof.

The dot-dash broken lines illustrate the boundary of the design and form no part of the claim. The remaining broken lines illustrate portions of the canopy for a vehicle, truck, light delivery vehicle or similar vehicle and form no part of the claimed design.
